UNITED STATES PATENT OFFICE.

EDWARD J. KNAPP AND ANNA C. WILMOT, OF CHICAGO, ILLINOIS, ASSIGNEES TO THE ADAMS & WESTLAKE COMPANY, OF SAME PLACE.

DESIGN FOR A FINIAL FOR BED-PILLARS.

SPECIFICATION forming part of Design No. 31,559, dated September 26, 1899.

Application filed August 22, 1899. Serial No. 728,140. Term of patent 31 years.

To all whom it may concern:

Be it known that we, EDWARD J. KNAPP and ANNA C. WILMOT, citizens of the United States of America, and residents of Chicago, county of Cook, and State of Illinois, have invented and produced a new and original Design for Finials for Bed-Pillars, of which the following is a specification, reference being had to the accompanying drawings, forming a part thereof.

In the drawings we have shown two views of the design in elevation, Figure 1 representing the design in side elevation, and Fig. 2 representing an elevation of the same in edge view.

As shown in the drawings, the leading or material feature of our design consists in a substantially cylindrical column slightly curved through its body portion and at its upper end terminating in a drooping acanthus leaf, the end of the leaf being curved backwardly to the body portion.

Minor accessories of the design are a raised belt following the median line of the acanthus leaf and bearing thereupon a longitudinally arranged series of raised nodules, rounded or partly spherical in form, a beading near the base of the columnar portion of the design, and a rosette at each side of the base of the acanthus leaf, each rosette comprising a substantially circular field upon which there is a central circular knob from which radiate upon the field a plurality of petals flanked by curved coves, the base of each petal being pierced by a star-point. 30 35

We claim as our invention--

The design for the finial of a bed-pillar, substantially as shown and described.

EDWARD J. KNAPP.
ANNA C. WILMOT.
